UNITED STATES PATENT OFFICE.

ERNEST BENSON, OF VALLEY CITY, NORTH DAKOTA.

CRATE.

Application filed March 1, 1922. Serial No. 540,270.

To all whom it may concern:

Be it known that I, ERNEST BENSON, a citizen of the United States, residing at Valley City, in the county of Barnes and State of North Dakota, have invented a new and useful Crate, of which the following is a specification.

My invention relates to shipping crates of the collapsible type and the object is to provide a simple, efficient and durable crate particularly adaptable for shipping fowl, pigs, lambs and any small sized live stock.

In the accompanying drawing:

Fig. 1 is a top view of my improved crate set up and one end partly opened, some minor parts being omitted.

Fig. 2 is a side view of Fig. 1 and showing a pig within the crate.

Fig. 3 is an edge view of the crate in its folded condition, the wire netting being omitted.

Fig. 4 is an end view of the crate in partly folded position and showing the near end portion swung up vertically on its hinge.

Fig. 5 is an enlarged section on line 5—5 in Fig. 2.

Fig. 6 is an enlarged section on line 6—6 in Fig. 2.

Fig. 7 is an enlarged detail elevation on line 7—7 in Fig. 2.

Referring to the drawing by reference numerals, the crate is preferably made in the form of an elongated box, the bottom or floor 8 being made of wood and having cross cleats 9; the top, sides and ends are made of heavy wire netting as illustrated and assembled as follows:

The top comprises a rectangular frame 10 preferably made of pipe over which is stretched the wire netting 11, the ends of the wire encircling the pipe in any suitable manner so as to hold the netting taut on the frame.

The sides comprise each an upper longitudinal section, of netting, and a similar lower section 12^a, both hingedly united by having their adjacent wire ends wound around a pipe 13 which is longer than the frame and protrudes from both ends thereof (see Figs. 1 and 2). The upper wire ends of section 12 are secured about the top frame bar 10 and the lower wire ends of section 12^a are secured about a lower frame pipe 14 corresponding to upper frame 10. The frame 14 is secured to the floor section 8 by means of eye bolts 15.

Endwise movement of pipe 13 is prevented by placing a collar 16 on each of them at any suitable place between the wires of the netting (see Figs. 1, 2 and 3) and held by a set screw 17.

The end walls are each made of a size corresponding to the height and width of the previously described parts. The frame part 18 however may be made of round bar stock and forming a U-shape the ends of which have loops 19 pivotally engaging the end portions of the top frame 10. The end frames also have wire netting of the same kind as used in the sides and top. The legs 70 of the end frame 18 are bent to form loops 18^a spaced so that they encircle the ends of the corresponding side hinge bars 13 when said end sections are swung into place (see Figs. 1 and 2) and helping to hold the crate 75 upright and rigid when set up.

On each end section I provide a strap iron 20 straddling frame 18 and secured by rivets 21 and having opposite loops 22 just outside the frame engaged by hasps 22^a 80 adapted to straddle a staple 23 secured in a bar 24 suitably located and secured on side members 12^a (see Fig. 2). Each hasp may be held in place (see to the left in Fig. 2) by a cotter pin 25 secured to a chain 26, the latter having its opposite end secured to the frame 14. Or any other suitable locking means may be used.

At a certain distance from each end of the floor I secure transversely on same, a strap iron 26^a the ends of which are turned up and looped about the lower frame bar 14 (see Figs. 2, 3 and 5). The upright arms are provided each with an outwardly extending staple 27 on which the hasps 22^a engage when the crate is folded.

The setting up of the frame is clear in Figs. 1 and 2, the sides being held in vertical relation by the end sections locked thereto and by the pipes 13 engaging in the loops 18^a of the end sections. The protruding ends of the pipes 13 can be used as handles in carrying the crate. In folding up the crate the end sections are first swung out and up (see Fig. 4) and the side sections bent inwardly and together until the top and sides are practically flat down upon floor 8. Then the end walls are laid back on the top (see Fig. 3) and the hasps 22^a can be swung down to engage the staples 27, as previously described, and locked by the cotter pin 25 or other suitable means. The crate is then

ready to be returned to the shipper and occupies a comparatively small space.

Having thus described my invention what I claim is:

5. 1. In a collapsible crate of the class described, a solid floor member, a rectangular frame secured upon the floor along its edges and in spaced relation to the floor, a top frame corresponding in size to the first mentioned frame, side body members comprising each two sections hingedly connected at their adjacent edges and at their opposite edges to the top and bottom frames, end sections pivotally secured to the ends of the 10 top frame, means for holding the sides and ends in their respective vertical planes when the crate is in erected position and means for locking the crate in collapsed, folded position, said members of the side sections 15 comprising wire netting the adjacent vertical wire ends of which are wound around the pintle bar of the middle hinge of each side, and the opposite ends of said wires being pivotally secured respectively, the upper section wires to the top frame and the 20 lower section wires to the lower rectangular frame adjacent the floor, and said pintle bar in each side protruding beyond the main 25

frame at both ends, and providing handles for carrying the crate, and rigid loops on 30 the edges of the end frames adapted to engage said pintles, when the frame is set up, and means for locking said end sections to the adjacent side sections in rigid relation thereto.

2. In a collapsible shipping crate, a top and bottom, side sections hinged to the top and bottom sections and having each an intermediate horizontal joint with a pintle rod extending beyond the ends of the section, end sections hinged to the top section and having eyes arranged to receive the ends of the pintle rods and thereby hold the side sections in a vertical plane when the end sections are in vertical position, and means for securing the end sections in said vertical or set-up position, said end extensions of the pintle rods being long enough to constitute handles for carrying the crate.

In testimony whereof I affix my signature.

ERNEST BENSON.
